GEORGE BEATTY, OF CARROLLTON, OHIO.

Letters Patent No. 69,164, dated September 24, 1867.

IMPROVEMENT IN SHEEP-SHED AND RACK.

The Schedule referred to in these Letters Patent and making part of the same.

TO ALL WHOM IT MAY CONCERN:

Be it known that I, GEORGE BEATTY, of Carrollton, in the county of Carroll, and in the State of Ohio, have invented a new and improved Combined Sheep-Shed and Rack; and I do hereby declare that the following is a full, clear, and exact description thereof, reference being had to the annexed drawings, making part of this specification, in which—

Figure 1 is a partial elevation.

Figure 2 an end view, and

Figure 3 a cross-section of my improved combined sheep-shed and rack.

Figure 4 is a section showing two sheds and racks combined under one roof, and affording loft-room for storing hay, fodder, roots, and sheep-feed of all kinds.

The nature of my invention consists in so preparing a shelter-shed and feeding-rack for sheep that it may be cheaply and expeditiously built, and be so arranged as to give the animals thorough ventilation without exposure to inclement weather, prevent them from being crowded, and allow them to be sufficiently fed in a cleanly manner with whatever food they may require, without waste, without going among them, and in less time than is required by any arrangement now in use.

In the drawings, A A are two posts, of a row of say one hundred to one hundred and fifty feet in length, placed ten feet (more or less) apart, and about seven feet high above the ground. They support a "plate," B, extending along their tops, on which the front and upper edge of the roof will rest, while it slopes back and downward to another plate, B', fig. 3, running along the tops of shorter posts A', placed opposite to and about six feet (more or less) from the posts A. A trench is dug outside of both rows of posts, front and rear, along the entire length of the shed, and the earth taken from it will be thrown upon the floor of the shed, so as to raise it above the adjacent ground and keep it always dry. The back of the shed should be boarded up so as to leave openings at the joints, for ventilation, between the edges of the boards, whether they are placed vertically or otherwise. One end of the shed will be closed in a similar manner, and the other will have a door, as shown in fig. 2, or be closed with movable rails. The object of giving so little room in width as six feet is to prevent more than three or four sheep from being crowded crosswise the shed. The length of the shed will never permit them to crowd endwise. As the front of the shed is open they do not require for healthful purposes a greater height than that named.

An extra roof, C, made in lengths to suit the distance between the posts A, is hinged to the roof proper, so that it may be let down to cover the front of the shed when desired. It will generally, however, be kept propped up as in fig. 2.

In front of the shed, between every two posts, is a feed-rack, by which all the sheep in the shed may be fed with any kind of food they may require nearly at the same time. Each rack—there being as many as there are posts, less one—is supported on two standards, D, and consists of a rail, a, and a shelf, b, which slopes slightly down towards the side next the shed. Bars c c, far enough apart to admit the head of a sheep between them, are placed vertically between the rail a and the lower edge of the shelf b. A board, b', swinging on joints at its ends in cleats secured to the standards, forms the back of the rack a b c, which is intended to receive only "long feed," such as hay, fodder, &c. When such food is supplied the back-board is let down, as shown in fig. 3, and the proper quantity placed on it and on the shelf b. The back-board is then put up again, crowding the food against the bars c, and preventing the animals from pushing it back with their heads. The rack is easily cleaned after the back-board b' is let entirely down. Hooks d, pinned to the posts A, hold the rack from being pushed away by taking hold of pins on the standards D.

A trough, E, extends along the whole length of the rack, under the shelf b, and rests on a rock-shaft, having its bearings in cleats on the outside of the standards. A lever, e, at one end of the rock-shaft, gives the means of vibrating the trough, so that it may be inaccessible, as shown in dotted lines, fig. 2, where its inner edge is closed against the under side of the rack, or be open to the sheep, as in fig. 3. This trough is intended to hold no food but grain, meal, roots, or other "short feed," and is habitually kept in the position shown in fig. 2, in order to keep the sheep from trampling in it, and to prevent it from becoming foul. It is only turned to the sheep when they are to be fed from it, and not then until every trough has had its proper quantity

distributed through its length, when they will be turned as rapidly as possible, for the purpose of insuring uniformity in feeding.

It will be found convenient, where a large number of sheep are to be sheltered, to divide the line of shed into two lengths, letting them face each other, about thirty feet apart, so that there may be room between for a hay-rick and a wagon-way for hauling to and from the sheds and racks.

Under some circumstances sheep-sheds may be constructed as shown in fig. 4, where two rows of sheds and racks are combined under one roof, with space between the roofs of the sheds and the covering roof for the storage of food for the sheep.

In the spring, when the sheep are turned out, the racks will be turned down on the floor of the shed, as in fig. 4, and the extra roof C let down, so as to cover the front of the shed.

Having thus fully described my invention, what I claim therein as new, and desire to secure by Letters Patent, is—

The vibrating feed-trough E, and rack D a b b' c, arranged and operating substantially as described, in combination with a sheep-shed, as set forth.

In testimony that I claim the above-described improvement I have hereunto signed my name this 12th day of August, 1867.

GEO. BEATTY.
